US0D1098276S

(12) United States Design Patent (10) Patent No.: US D1,098,276 S
(45) Date of Patent:  Oct. 14, 2025

(54) BANK OF GAMING MACHINES INCLUDING LIGHT BAR

(56)

(57) CLAIM

The ornamental design for a bank of gaming machines including light bar, as shown and described.

DESCRIPTION

The present application is also related to U.S. Design patent application Ser. No. 29/735,056, filed May 18, 2020, entitled “Bank of Gaming Machines Including Light Bar,” U.S. Design patent application Ser. No. 29/735,058, filed May 18, 2020, entitled “Bank of Gaming Machines Including Light Bar,” U.S. Design patent application Ser. No. 29/735,063, filed May 18, 2020, entitled “Bank of Gaming Machines Including Light Bar,” U.S. Design patent application Ser. No. 29/735,065, filed May 18, 2020, entitled “Bank of Gaming Machines Including Light Bar,” U.S. Design patent application Ser. No. 29/735,067, filed May 18, 2020, entitled “Bank of Gaming Machines Including Light Bar,” U.S. Design patent application Ser. No. 29/735,035, filed May 18,

2020, entitled “Bank of Gaming Machines Including Light Bar,” and U.S. Design patent application Ser. No. 29/735,069, filed May 18, 2020, entitled “Gaming Machine Including Light Bar,” the disclosures of which are hereby incorporated by reference in their entireties

FIG. 1 is a perspective view of a bank of gaming machines including light bar showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another front view thereof, illustrating the light bar in an illuminated state.

In these drawings, the solid lines illustrate the claimed ornamental design, whereas broken lines illustrate unclaimed environmental features and form no part of the claimed design. The radiating lines emanating from the light bar in FIG. 8 represent illumination.
